191,398

COMBINED ELECTROMAGNET AND HOUSING THEREFOR

Hugh J. Hall, Los Altos, Calif., assignor to Varian Associates, Palo Alto, Calif., a corporation of California

Filed Feb. 20, 1961, Ser. No. 63,999

Term of patent 14 years

(Cl. D26—1)

FIG. 1

FIG. 2

FIG. 3

FIG. 1 is a perspective view of a combined electromagnet and housing therefor showing my new design;

FIG. 2 is a front elevational view thereof; and

FIG. 3 is a side elevational view thereof, the opposite side being substantially a mirror image.

I claim:

The ornamental design for a combined electromagnet and housing therefor, as shown and described.
